TOOTH POWDER DISPENSER

Dean Marshall, Centralia, Wash.

Application June 29, 1953, Serial No. 25,704

Term of patent 7 years

(Cl. D4—3)

To all whom it may concern:

Be it known that I, Dean Marshall, a citizen of the United States of America, residing at Centralia, in the county of Lewis and State of Washington, have invented a new, original, and ornamental Design for a Tooth Powder Dispenser, of which the following is a specification, reference being had to the accompanying drawings forming a part thereof, in which

Figure 1 is a side elevational view of a tooth powder dispenser showing my new design;

Fig. 2 is a front elevational view thereof; and Fig. 3 is a top plan view thereof.

I claim:

The ornamental design for a tooth powder dispenser, as shown.
